Des. 228,591
Patented Oct. 16, 1973

228,591

LOUNGE CHAIR

Don Ray Gill, Hammond, Ind., assignor to Mohasco
Industries, Inc., Amsterdam, N.Y.

Filed June 1, 1971, Ser. No. 149,111

Term of patent 14 years

Int. Cl. D6—02

U.S. Cl. D6—39

The figure is a perspective view of a lounge chair illustrating my new design.

The back of the chair is conventionally plain while the side not shown is substantially identical to the side shown.

I claim:

The ornamental design for a lounge chair, as shown and described.
